HAIR CURLING MANDREL

Rocco Pezzella, Washington, D. C.

Application January 16, 1935, Serial No. 2,095

19 Claims. (Cl. 132—33)

The present invention relates to mandrels on which locks of hair are wrapped to be treated and curled.

One of the primary objects of the invention is to provide means where the coiled hair after it has been wrapped on the mandrel, can be placed under additional tension so as to insure that the coil is very tightly wrapped—a condition that is essential to the best results, and one that so far as I know has heretofore been accomplished only by putting tension on the hair as the lock is wrapped.

A further and important object is to provide effective means for clamping the base portion of the lock so that the danger of pulling the hair and causing inconvenience to the person whose hair is being treated, is eliminated and at the same time the mandrel is effectively secured in place.

20 A still further object is to provide novel and effective means for securing the free end portion of the lock of hair after it has been wrapped on the mandrel.

In the accompanying drawings:

25 Figure 1 is a view in elevation of the preferred embodiment of the invention showing a lock of hair wrapped thereon.

Figure 2 is a longitudinal sectional view through the same.

30 Figures 3 and 3a are cross sectional views taken on the lines 3—3 and 3a—3a of Figure 1, respectively.

Figure 4 is a longitudinal sectional view on the line 4—4 of Figure 1.

35 Figure 5 is a cross sectional view taken on the line 5—5 of Figure 1.

Figure 6 is a longitudinal sectional view of the body section of the mandrel with the stretcher section removed and showing the hair clamping 40 jaw and sleeve carrying the same.

Figure 7 is a perspective view of the head portion of the mandrel.

Figure 8 is a detail view partly in section of the hair-clamping jaw and sleeve.

45 Figure 9 is a sectional view of the holding collar for said sleeve and jaw.

Figure 10 is a detail sectional view of the hair stretching section of the mandrel.

50 Figure 11 is a face view of the same.

Figure 12 is a plan view of the clamping device for the free end of the lock.

In the embodiment disclosed the mandrel is composed of two sections, which for the purposes of distinction are designated as the body section

and the stretcher section. The body section is designated 13 and is in the form of a rod having a head 14 at one end and a longitudinal cutaway portion 15 at its other end. The head is connected to the main portion of the section by a 5 recessed part 16, providing a chamber or space 17 with an entrance mouth 18. This head portion has an extension 19 partly extending across the chamber and creating a hooked formation.

The head 14 has an annular channel 20 cut 10 across on one side by a recessed hair-receiving seat 21 that opens into one side of the chamber 17 (see Figure 7). The inner end of the head is beveled, as illustrated at 22, and said end has an annular groove 23 on the outer side of 15 the portions 16 and 19. A sleeve 24, slideable longitudinally upon the body section 13, is movable across the entrance mouth 18, and the adjacent end will enter the groove 23. This sleeve carries a crescent-shaped hair-clamping jaw 25 20 operating in the chamber 17, and cooperating with the adjacent end wall of the head 14 to grip a lock of hair passed through the chamber, as illustrated in Figure 4. The sleeve is held with the jaw in its active or clamping position by 25 means of a collar 26 that is threaded, as illustrated at 27 on the body section 13, and being movable longitudinally of said section, abuts the sleeve to hold it and the clamping jaw in co-operative relation as shown in Figures 2 and 4. 30

The reduced portion 15 of the body section provides a chamber 28, and in this chamber is placed the stretcher section of the mandrel, said stretcher section being designated 29. Its outer surface has a contour corresponding to the 35 cylindrical form of the body section, and it is laterally movable, or in other words, separable from the portion 15. For this purpose, at one end it rides upon an outwardly projecting guide pin 30, and its other end may be slidably mounted 40 on an inwardly extending pin 31 carried by a bracket 32 secured to the end of the body section. The stretcher section 29 is provided with recesses 33 through which the said pins pass, and coiled springs 34, placed in the recesses and surrounding the pins, urge the stretcher section 29 outwardly. One end of this stretcher section is preferably provided with a lip 35 that overlies the main portion of the body section 13, said section having a recess 36 for the reception of the lip. The adjacent faces of the cut-away portion 15 and the stretcher section are provided with oppositely inclined ways 37 and 38 that are located in opposition, and wedges 39, operating 50

against these faces and movable longitudinally of the mandrel, serve to positively separate the cut-away portion and the stretcher section by moving the latter outwardly. These wedges may 5 be carried by a stem 49 which extends through the end of the mandrel and is threaded to receive a pulling nut 41 that abuts the end face of the mandrel.

The stretcher section 29 is provided in its opposite sides with longitudinal grooves 42 constituting trackways for a carrier block 43 which has ribs 44 on its inner sides that slidably engage in said grooves 42. This carrier block has outstanding spaced ears 45 between which is located the 10 ear 46 of a hair-clamping plate 47 pivoted, as shown at 48, to said ears 45. The plate is transversely rounded to substantially correspond to the form of a lock wrapped upon the mandrel and this plate can be clamped on the hair, or as shown in 15 Figure 2, by any suitable means, for example, a tension screw 49 threaded through a yoke 50 that overlies the plate and is mounted on the carrier.

For the purpose of additionally clamping the hair at its base and also securing the usual coverings in place, a ring is employed consisting of sections 51 hinged together at 52 and having their free ends adapted to be secured by a clamping bolt 53 (see Figure 3a).

In using the device, the base portion of a lock 30 of hair, namely, that portion adjacent the scalp is passed through the entrance mouth 18 and lies against the inner face of the head 14 within the chamber 17. The sleeve 24 is now moved across 35 the entrance mouth so that its end enters the groove 23 and the clamping jaw 25 will grip the hair by pressing it against the said inner face of the head (see Figure 2). The holding collar 26 is then threaded onto the main portion of the body section and by bearing against the adjacent 40 end of the sleeve 24 holds the jaw in its active or clamping position. The exterior surface of the mandrel as a whole is now of substantially unbroken cylindrical form and the free portion of 45 the lock is now wrapped snugly thereon in the usual manner, this coil extending over and around the cut-away portion 15 and the stretcher section 29. The carrier 43 is next moved forwardly and the clamping plate 47 pressed upon the free portion of the lock by the tension screw 49 so that the 50 free end portion of the hair is effectively secured. The wedges 39 are now drawn by turning the nut 41 so as to cause the stretcher section 29 to move outwardly and this will obviously place additional tension on the coiled lock, securing that tightness 55 which is so necessary to the best results. The usual treatment is then given, after which the covering, indicated at 54, is placed over the hair and the base of the lock is located in the seat 21 and is secured by the ring 51 placed in the groove 60 20, this ring also serving as a clamp for the covering and preventing the steam escaping from the interior of the covering 54 and injuring the adjacent portion of the scalp.

From the foregoing, it is thought that the construction, operation and many advantages of the herein described invention will be apparent to those skilled in the art without further description, and it will be understood that various 65 changes in the size, shape, proportion, and minor details of construction may be resorted to without departing from the spirit or sacrificing any of the advantages of the invention.

What I claim is:

1. A mandrel comprising a body section having

a longitudinally disposed reduced portion, a stretching section extending along the reduced portion and laterally movable with respect thereto, said sections being adapted to have a lock of hair wrapped around both, and spring means interposed between the sections for automatically separating them to place tension on the wrapped hair.

2. A mandrel on which hair is to be wrapped having a hooked end portion for receiving a lock of hair, and a sleeve slidably on the mandrel and movable to a position over the hooked portion to completely enclose the same, said sleeve having a hair clamping device movable in the hook recess.

3. A mandrel on which hair is to be wrapped having a hooked end portion for receiving a lock of hair, and a sleeve slidably on the mandrel and movable to a position over the hooked portion to completely enclose the same, said sleeve having a hair clamping jaw behind the enclosing portion that operates in the hook recess, and cooperates with the end wall of the hook to clamp the hair, and means for securing the sleeve and jaw in clamping relation.

4. A mandrel on which hair is adapted to be wrapped having a head at one end, and a recess behind the head for the reception of a lock of hair to be wrapped on the mandrel, and means on said head and coating therewith for clamping in the recess against the head the hair that is extended across the head and laid in said recess.

5. A mandrel on which hair is adapted to be wrapped having a head at one end, said head having an annular groove and a hair receiving seat traversing the same, and means that engages in the groove for clamping against the head the hair located in the seat.

6. A mandrel on which hair is adapted to be wrapped having a head at one end, said head having an annular groove and a hair receiving seat traversing the same, said mandrel having a transverse recess beside the head through which the hair laid in the seat is adapted to pass, a sleeve slidably on the mandrel and movable across the recess, said sleeve having a clamping jaw that holds the hair placed in the recess, and a detachable hair clamping ring that engages in the head of the groove and overlies the hair in the seat for clamping said hair.

7. A mandrel on which hair is adapted to be wrapped, a swinging clamping device for the free end of the hair, and means for positively pressing said clamping device upon the end portion of the hair after the same has been wrapped upon the mandrel.

8. A mandrel on which hair is adapted to be wrapped, a movable clamping device for the free end of the hair, means for pressing said clamping device upon the end portion of the hair after the same has been wrapped upon the mandrel, and a carrier on which said clamping device is movably mounted, said clamping device being movable longitudinally along the mandrel.

9. A mandrel on which hair is adapted to be wrapped, means for fastening the base portion of a lock of hair to one end of the mandrel, a carrier slidably along the other end portion of the mandrel toward and from the hair wrapped thereon, a hair clamping device pivoted on the carrier and means for holding the clamping device on the lock after the same has been wrapped on the mandrel.

10. A mandrel on which hair is adapted to be wrapped, comprising separable sections, means

for separating the sections to place tension on the lock of hair wrapped on the mandrel, and hair clamping means mounted on one of the sections and movable longitudinally along the same.

5 11. A mandrel on which hair is adapted to be wrapped, comprising a body section having a longitudinally disposed reduced portion and a stretching section on the reduced portion and separable therefrom, means interposed between 10 the sections for separating them to tension the hair after it has been wrapped about both sections, a head on one end of the mandrel having an annular groove and a transverse recessed hair receiving seat traversing the groove, said mandrel 15 adjacent the head having a transverse hook shaped hair receiving recess communicating with the aforesaid seat, a sleeve slidable on the mandrel and movable over the recess, said sleeve having a hair clamping jaw movable in the recess, 20 a carrier slidable longitudinally on the hair stretching section of the mandrel, a hair clamping plate pivoted to the carrier and adapted to overlie the end portion of the hair wrapped about the sections, and means for pressing the plate 25 upon the hair to hold the latter.

12. A hair curling mandrel comprising a body section, a hair stretching section located longitudinally along the same and movable toward and from the body section, and yielding means interposed between the body section and hair stretching section to automatically urge them apart.

13. A hair curling mandrel comprising a body section, a hair stretching section located longitudinally along the same and movable toward and from the body section, guides for slidably directing the stretching section, and springs on the guides having bearings against the stretching section and operating to urge the body portion and stretching section apart.

40 14. A hair curling mandrel comprising a body section, a hair stretching section located longitudinally along the same and movable toward and

from the body section, yielding means interposed between the body section and hair stretching section to automatically urge them apart, and means supplementary to the yielding means for positively separating the body portion and stretching section. 5

15. A hair curling mandrel having a head at one end and a transverse hair-receiving recess behind the head, means on the head for clamping a lock of hair laid across the same and engaged in the recess, a sleeve slidable on the mandrel and movable across the recess to substantially cover the same, and means within the sleeve for clamping the hair laid in the recess. 10

16. A hair curling mandrel having a head at one end and a transverse hair-receiving recess behind the head, and a movable jaw extending across the recess and coacting with the inner side of the head to clamp a lock of hair laid in the recess. 15

17. The combination with a mandrel on which hair is to be wrapped, of a carrier slidably mounted on the mandrel and a clamp for the free end of the hair movably mounted on the carrier and movable with the mandrel to different positions to clamp upon the free ends of hair of different lengths. 20

18. The combination with a mandrel on which hair is to be wrapped, of a pivotally mounted hair clamping device mounted thereon, a yoke overlying the clamping device, and means on the yoke engaging the clamping device for holding it in a clamping engagement with the hair. 25

19. The combination with a mandrel on which hair is to be wrapped, of a carrier slidably mounted on the mandrel, a clamping device pivotally mounted on the carrier, a yoke overlying the clamping device, and a device on the yoke engaging the clamping device for holding it in clamping engagement with the hair. 30

ROCCO PEZZELLA.
